T. S. PURNIS

TOOL FOR PLANING VALVE SEATS

Filed July 1, 1926

UNITED STATES PATENT OFFICE.

THEODORE S. PURNIS, OF ABERDEEN, SOUTH DAKOTA, ASSIGNOR TO THE K. O. LEE & SON COMPANY, OF ABERDEEN, SOUTH DAKOTA, A CORPORATION OF SOUTH DAKOTA.

TOOL FOR PLANING VALVE SEATS.

Application filed July 1, 1926. Serial No. 119,909.

This invention relates to a device for planing valve seats of internal combustion engines.

An object of the invention is the provision of a device which is adapted to accommodate blades of various characters for planing simultaneously the inner and outer edges of a valve seat of an internal combustion engine preparatory to planing said seat for properly accommodating the valve and preventing the loss of fluid past the same, the last operation requiring separate treatment.

A further object of the invention is the provision of a conically shaped cutter head, the conical surface of which is at a different pitch from the cutting edges of the cutters to be used, and adapted to act as a guide and limit the depth of the cut when it becomes seated in an opening in the cylinder block which is at the outer end of an intake or exhaust passage, said cutter head being so constructed as to receive and hold a plurality of cutting blades for performing various operations to reduce the width of the old valve seat and replane the seat to a condition where it will properly seat the valve.

This invention will be best understood from a consideration of the following detailed description, in view of the accompanying drawings forming a part of the specification; nevertheless it is to be understood that the invention is not confined to the disclosure, being susceptible to such changes and modifications which shall define no material departure from the salient features of the invention as expressed in the appended claim.

In the drawings:

Figure 1 is a view in elevation of the planer constructed in accordance with the principles of my invention and equipped with a cutting blade for planing the outer edge of the seat.

Figure 2 is a view in elevation of the device equipped with a cutting blade for planing the inner edge of the seat.

Figure 3 is a fragmentary sectional view showing the method of locking the cutting blades in the cutter head.

Figure 4 is a horizontal section of the planing device.

Figure 5 is a fragmentary vertical section showing the valve seat after the same has been completely planed.

Referring more particularly to the drawings, 10 designates a cylinder block having an exhaust or intake passage shown at 11. When the valve seat becomes so badly worn that it is enlarged in area it is necessary therefore to plane on opposite sides of the seat in order to reduce the width of the seat so that the valve may properly be positioned and snugly engage all parts of the seat. In order to accomplish this result I have provided a conically shaped cutter head 12. This cutter head has a vertical slot 13 adapted to receive a blade or cutter 14 which has a cutting edge 15 adapted to remove a portion 16 from the outer edge of the seat 17 in the first step in the process for reducing the width of the seat.

Adjacent the slot 13 is a slightly tilted passage 18 adapted to receive a pin 19 which has a flat face 20 engaging the cutter blade 14 when the pin is driven into the passage whereby, after the blade has been properly adjusted, the wedging action of the pin will maintain the blade against displacement.

A second slot 21 is formed vertically and radially of the head and is likewise provided with a slightly tilted passage 22 opening into the slot 21 and adapted to receive a pin 23 for wedging a blade 24 in the slot 21 against movement when the head 12 is rotated. The side or cutting edge 25 of the blade 24 is inclined at an angle to the vertical and produces a cut as shown at 26 in Figure 5 for aiding in reducing the width of the seat 17. This cut, as is shown, is made at the inner edge of said seat.

Both of the blades 14 and 24 have their rear edges in snug engagement with the rear vertical wall 27 of either of the slots 13 or 21 as the case may be and this aids in cooperation with the pins for maintaining the adjustment of the blades.

By similarly providing a third slot a third blade may be inserted for replanning the valve seat at the pitch of the valve to be seated therein but this is not shown in the drawings.

The cutter head is held in position by means of a centering pin 28 which has an enlargement, as shown at 29, adapted to be engaged by some suitable tool for turning the same whereby the threads 30 of the upper end of the pin is screwed into the threaded opening in the center of the cutter head. The pin 28 is adapted to be received within

a passage 31 in which the usual valve stem of the engine is adapted to be reciprocated. This pin aids in maintaining the cutter head centered over the valve seat.

6 A shank 32 is screwed or secured in any approved manner in the upper portion of the head and rises centrally therefrom. The extreme upper end is provided with a polygonally faced portion 33 adapted to be engaged by a suitable tool for turning the same if desired, otherwise a bar may be inserted through a passage 34 in the upper end of the shank whereby the same may be turned.

10 It will be noted by my improved tool that 15 all of the cutter blades for performing different parts of the operation may be used at the same time, or, only one cutter blade may be used at a time, but, in the practical performance for the operation it will be found 20 that blades 14 and 24 for planing at the inner and outer edges of the old valve seat may be used at the same time and readily operated by hand, while the tool for replanning the valve seat to the pitch of the valve 25 to be seated therein can be more satisfactorily used in a separate operation. Due to 30 particular reception of the pin 28 in the passage 31, the cutter will be maintained properly positioned at all times during the operation 35 of the device, while the conical faced portion 35 of the cutter head, being at a different pitch from the cutting edges of any of the cutter blades, will limit the depth of the cut when it becomes seated in the opening in the exhaust or intake passage.

The cutter blades to be inserted in the vertically and radially disposed slots in the cutter head are tapered from their inner thicker edge to the outer thinner edge so that when 40 the pins are forced into the respective slanting holes opening into said vertical passages, the pins will tend to force the blades inwardly against the inner wall of the passage and prevent displacement of the blades. An 45 important feature of the tool is that the conical portion 35 serves, not only as a receptacle for the cutting blades, 14 and 24, but

also as a guide and gauge to determine the diameter of the upper outside edge and also of the lower inner edge of the valve seat 17 50 as indicated in Figure 5.

55 Referring to Figure 1 it will be seen that when downward pressure is applied and the tool rotated, cutting edge 15 continues cutting at 16 until the conical portion 35 rests on the valve seat surface 17. When the conical portion 25 rests entirely on the surface of the valve seat 17, the cutter blade ceases to cut, hence, it is obvious that the same operation repeated on the other valve seats 60 with no change or readjustment of the cutter blade 14 will insure identically the same diameter of the upper outer edge of the valve seat 17. This result can be obtained only when the conical portion 35 has a different angle than the cutter blade 14, serving as a gauge for same.

65 What I claim is:

A device of the character described for 70 planing the passage in a cylinder block having 75 a valve seat in the outer end of the passage and comprising a cutter head having a cylindrical upper portion and a conically shaped lower portion, said conically shaped head being provided with vertical slots disposed radially, each slot opening through the outer wall of the head with the inner wall of the slot being located adjacent the center, a cutter blade mounted in each radial slot, said head being provided with a passage slanting into each vertical slot at one side thereof, a pin forced into each slanting 80 passage and provided with an inclined face 85 engaging a cutter blade for forcing the cutter into engagement with the rear wall of the vertical slot, means for rotating the cutter head, one of the cutter blades being 90 adapted to be disposed within the passage in the cylinder block and adapted to plane the wall of the passage simultaneously with the planing of the valve seat by the other cutter blade.

95 THEODORE S. PURNIS.
